UNITED STATES PATENT OFFICE.

JAMES N. WHITMAN, OF PHILADELPHIA, PENNSYLVANIA.

GAS-PRODUCING APPARATUS.

No. 863,817.

Specification of Letters Patent.

Patented Aug. 20, 1907.

Application filed September 1, 1906. Serial No. 332,897.

To all whom it may concern:

Be it known that I, JAMES N. WHITMAN, a citizen of the United States, residing in the city of Philadelphia, county of Philadelphia, and State of Pennsylvania, have invented certain Improvements in Gas-Producing Apparatus, of which the following is a specification.

This invention is a gas producing apparatus designed primarily to regulate the fuel feed, the ash removal, and the gas production to the demand for the product, it being a leading object to meet the need in gas engines, lighting and heating plants for a steady supply of gas automatically regulated to the requirements of the apparatus supplied.

15 To these ends the apparatus comprises a closed chamber for the combustion of fuel and jacketed to permit the circulation of water around it so as to regulate the temperature and prevent loss of heat, and mechanism for feeding fuel and withdrawing ashes 20 continuously at a regulated rate varying with the supply of gas demanded.

In the accompanying drawings, Figure 1 is a diagrammatic representation of my invention in side elevation; Fig. 2 is a vertical sectional view through 25 the ash-hopper and water-seal of the producer at right angles to the view shown in Fig. 1, and Fig. 3 is a vertical sectional view through the ash-hopper and water seal of a modified construction.

Referring to the drawings, the combustion chamber 1 of the producer is formed by the shell 2, terminating in the shell 3, forming the ash holder which are inclosed by the shell 4, so as to produce the chamber 5 surrounding the chamber 1. A passage 6 leads to and a passage 7 leads from the chamber 5, whereby 35 the circulation of water may be maintained at a temperature such as to prevent the loss of heat and act toward maintaining the desired temperature in the chamber. A passage 8 leads from the otherwise closed top of the chamber 1 to the bottom of the scrubbing 40 or purifying chamber 9 and a branch passage 10 leads to the atmosphere, the passages being controlled by the two-way valve 11. From the top of the chamber 9, a passage 12 leads to the gas holder 13, which is connected by the passage 14 with the engine or apparatus 45 in which the gas is utilized. A blower 15 is placed in the passage 12 to provide the necessary exhaust for drawing the air into the chamber 1 through the bottom of the ash holder and the gas producer through the passage 8, the chamber 9 and the passage 12 to the holder 13. The same function may be performed by 50 suction communicated to the system through the passage 14 from the engine or other apparatus. A passage 16 leads from the holder 13 into the ash-holder where gas which may flow through this passage may

be delivered under the dome 17, the passage being 55 controlled by a relief valve 18 opening when subject to sufficient pressure from the gas in the holder.

Extending through the lower part of the producer body is a duct 19 having the opening 20 centrally disposed with reference to the chamber 1 and the hoppers 60 21 exterior to the body. In the duct are the rams 22 and the pistons 23, respectively connected by the rods 24, the rams being reciprocated by the pistons, which are operated under control of the valves 25 for admitting steam or air to the chambers 26, at the ends of the duct 65 in which the pistons work. The air or steam for the operation of the mechanism is supplied through the passage 27 having the branches 28 which communicate with the respective valves. The passage 27 is controlled by a valve 29 connected through the arm 30, the 70 link 31 and the lever 32 fulcrumed on the strut 33 with the diaphragm 34, the latter acting under pressure communicated from the holder 13 by way of the diaphragm chamber 35 connected therewith.

Exterior to the base of the producer are the sprocket-wheels 36, which carry the belt 37 having thereon the scrapers 38 traveling under the dome 17 by which ashes are removed from the hopper 3 and the sealing pit 39 beneath it. A shaft 40, on which one of the wheels 36 is fixed, has a beveled gear 41 thereon, which is driven 75 by a beveled gear 42 fixed to a ratchet-wheel 43. The ratchet-wheel is engaged and operated in one direction by the pawl 44, connected to a lever 45 which is fulcrumed on the strut 46, the lever being connected to the piston stem 47, whereby the rams 22 for feeding the coal 80 and the scrapers 38 for removing the ashes are operated together by the connecting mechanism. As the operation of fuel feeding mechanism and the ash removing mechanism are under control of the valve 29, the position of which depends upon the pressure in the gas 85 holder 13, or otherwise the rate at which the gas is being withdrawn therefrom, the rate of feeding, removing ash and producing gas will be both continuous and variable with the consumption of gas. When the consumption of gas is stopped the valve 29 is closed and the valve 18 90 is opened, by the increased pressure in the gas holder 13, upon which the gas may flow through the passage 16 to the ash pit 3, through the combustion chamber 1, the passage 8, chamber 9, and passage 12, by which an open or relief circuit is provided.

100 It will be understood that the details of construction may be modified, as in Fig. 3 for example, in which oppositely pitched screws 48 revolved by a shaft 49 and a chain 50 connecting the wheels 51 and 52 on these shafts are substituted for the ram mechanism of Fig. 1.

105 Having described my invention, I claim:—

1. A gas producing apparatus comprising a combustion chamber, mechanism for feeding solid fuel into the com-

- 2.
- bustion chamber, and mechanism whereby the pressure of the gas produced controls the rate of feeding fuel.
2. A gas producing apparatus comprising a combustion chamber, connected mechanisms for feeding solid fuel to said combustion chamber and withdrawing ashes therefrom, a gas holder, a passage leading from said combustion chamber to said gas holder and a second passage leading from said holder back to said chamber.
3. A gas producer comprising a combustion chamber, means for feeding fuel to said chamber, fluid pressure mechanism for operating said feeding mechanism, a gas holder connected with said combustion chamber, and mechanism whereby the gas pressure in said holder controls said fluid pressure mechanism.
- 10 4. A gas producing apparatus comprising a combustion chamber, active mechanism for feeding solid fuel to said chamber, and mechanism under control of the pressure of

the gas produced in said combustion chamber for regulating the rate of operating said fuel feeding mechanism.

5. A gas producing apparatus comprising a combustion chamber, mechanism for feeding fuel thereto, a gas holder, a passage leading from the top of said combustion chamber to said gas holder, a further passage leading from said gas holder to said combustion chamber, an automatically operating valve for controlling said last named passage and mechanism controlled by the pressure of the gas for regulating the rate of the feeding mechanism.

In testimony whereof I have hereunto set my name this 31st day of August 1906, in the presence of the subscribing witnesses.

JAMES N. WHITMAN.
